UNITED STATES PATENT OFFICE.

JOHN R. WHITNEY, OF RADNOR, DELAWARE COUNTY, PENNSYLVANIA.

PROCESS OF AND MOLD FOR CASTING.

SPECIFICATION forming part of Letters Patent No. 352,792, dated November 16, 1886.

Application filed January 2, 1886. Serial No. 187,452. (No model.)

To all whom it may concern:

Be it known that I, JOHN R. WHITNEY, a citizen of the United States, residing in Radnor township, Delaware county, and State of Pennsylvania, have invented certain new and useful Improvements in Casting Metals, of which the following is a specification.

My invention relates to the construction of such castings as it is desirable to make in sections or with spaces between different parts too thin to be produced by the use of ordinary sand cores. It is applicable to a great variety of castings, but is designed to be applied especially to the manufacture of chills for railroad-car wheels, when it is required that they should be cut into sections on their inner surface, to allow them to freely expand and contract in the process of casting a wheel. Ordinarily for articles of this character a solid casting is first made, and after it is properly shaped to its required dimensions it is divided into the required sections by sawing through the metal at the desired points—an operation which involves considerable expense and labor. By my improvement such expense and labor are avoided, the chill being cut into sections by the process of casting, with intervening spaces between the sections no greater than saw-kerfs, and, if desired, very much less. To accomplish this I use thin blades or plates of asbestos paper, mica, or other equally refractory thin material, alone or in combination with sheet-iron or other stiffening material. These are placed in those positions in the mold where the parts of the casting should be separated from each other, and thus serve to prevent the molten metal from flowing together. Asbestos paper, or felt alone, or card-board, mica, sheet-iron, &c., with a coating of asbestos, are found so refractory that they effectually resist the action of the molten metal, and cores may thus be made extremely thin, so that the different sections may be cast in very close proximity to each other at the edges, but without possibility of union. In using such parting plates or pieces they may be embedded in the green-sand mold so as to extend into or across the mold, where desired, or they may be secured in or project from ordinary dry-sand cores.

While my invention is adapted for use in making a great variety of articles, I have illus-

trated it in the drawings in connection with means of casting the chills of car-wheels, Figure 1 being a transverse sectional elevation of such means; and Fig. 2, a sectional plan 55 on the line 1 2, Fig. 1. Fig. 3 is a section showing a modification. Fig. 4 is a side view of a dry-sand core supporting a thin blade of carbonized fiber or asbestos.

A represents the casting, B the sand, and a 60 the plates or blades of refractory material, arranged at the points where the casting must be divided, the whole being shown in a two-part flask resting on a bottom board.

It will of course be understood that where 65 minute slits or openings of irregular form are required to be made in the casting, this result is obtained by making the thin cores to correspond to the form and position of the openings required, the core, as usual, being put in place 7c after the pattern is withdrawn from the sand.

In Fig. 3 the blade a is shown extending from the sand at one side of the mold into a cylindrical core, so as to constitute a core for forming in the casting an opening communicating with 75 a slit extending to one side.

It should be understood that the iron or card-board is merely the support of the refractory material which protects the supporting-blade from the effects of the molten metal. It should 80 also be understood that under the head of "thin blades of refractory material" I include carbonized cloth, thin plates of clay, and other refractory substances.

In Fig. 4 the blade of asbestos, carbonized 85 paper, or other material is shown as secured in a dry-sand core, the latter constituting a frame supporting the blade, except at the point where the slot is to be situated.

I do not here claim supporting a thin core in 90 a frame or at the edges, as this forms the subject of a separate application for Letters Patent filed July 26, 1886, Serial No. 209,136.

Without limiting myself to any special arrangement of the parting or core pieces, or to 95 the use of any special material therefor, I claim—

1. The within-described improvement in the art of casting chill-molds for car-wheels, &c., the same consisting in dividing a mold into 100 sections by means of thin blades of asbestos paper or other equally refractory material, and

pouring the molten metal into the sections, substantially as set forth.

2. The combination, with a mold for casting chill-molds for car-wheels, &c., of thin blocks 5 or blades of asbestos or other refractory material, extending into the opening of the mold, so as to separate the parts of the casting, after the manner of a core, at the places where the blades are situated, substantially as and for the 10 purpose set forth.

3. The combination, with a mold for casting chill-molds for car-wheels, of thin blocks or blades of asbestos or other equally refractory material extending from the sand into the 15 mold-opening, substantially as set forth.

4. The combination, with a mold for casting chill-molds for car-wheels, of thin plates or blades consisting, in whole or in part, of asbestos or other equally refractory thin material embedded in a dry-sand core or frame and 20 placed in the mold, substantially as described.

In testimony whereof I have signed my name to this specification in the presence of two subscribing witnesses.

JOHN R. WHITNEY.
